ATTORNEY.

UNITED STATES PATENT OFFICE

ABRAHAM GOODMAN, OF BROOKLYN, NEW YORK, ASSIGNOR TO EMETH FINANCIAL CORPORATION, A CORPORATION OF NEW YORK

HAIR WAVER

Application filed February 19, 1932. Serial No. 593,964.

This invention relates to improvements in hair wavers or curlers comprising two pivotally connected spring pressed members or jaws of the type disclosed in the patent issued 5 to myself and Jacob Goodman on December 10, 1929, #1,737,301.

The principal object of the invention is to provide a device of this type with an elastic clamping cord which is self-conforming to 10 rolls of hair of different thicknesses and which is so arranged as not to disturb the wave or curl when the device is withdrawn or removed from the hair.

Another object of the invention is to provide 15 novel means for securing the elastic cord flexibly to the device in such manner that the parts may be easily assembled with a minimum amount of labor and at a low cost.

Other and further objects and advantages 20 of the invention will appear from the following description thereof, reference being had to the accompanying drawing, in which:—

Figure 1 a side elevation of a hair waver 25 embodying the invention and showing the elastic cord in open position;

Figure 2 a similar view of the device showing the elastic cord in closed or clamping position;

Figure 3 an enlarged detail view partly in 30 section;

Figure 4 a plan view of one end of the elastic cord.

Referring to the drawing, 10 indicates a 35 tubular member constituting one of the two coacting jaws of the device, and 11 indicates the second member or jaw which is convexo-concave in cross-section of such curvature as closely to embrace the upper half of the member 10 when said members are in their normally closed positions. The two members 40 are formed with overlapping ears 12 and are pivotally secured together by means of a pin or pivot 13 extending transversely 45 through said ears. Both members are pro-

vided with finger grip portions 14 at one side of their pivotal connection, each of which portions terminates in a lip or flange 15.

16 indicates an elastic cord preferably consisting of a core of rubber 17 having a woven fabric covering 18. The front end of the elastic cord has a metal tip 19 provided with a forwardly protruding lug 20 formed with a slot or opening 21. The rear end has a similar metal tip 22 preferably formed with a hook 23 adapted to catch in the open front end of the member 10 as seen in Figure 2. If desired, the hook 23 may be eliminated and the tip 22 may be of such diameter as to permit of its insertion directly into the open end of member 10.

24 is a leaf spring which is disposed between the finger grip portions 14 of members 10 and 11, with its ends abutting against the lips or flanges 15 of said portions. This spring functions normally to urge or press together the jaws or members 10 and 11.

In assembling the parts, the leaf spring 24 is inserted in the slot or opening 21, thus 70 flexibly securing the front end of the elastic cord to the spring. The spring is then slightly compressed and sprung into place between the finger grip portions 15 as clearly shown in Figure 1. This construction provides a very simple and highly efficient way 75 of securing the elastic cord to the device.

The manner of operation of the device is as follows:—The finger grip portions 14 are 80 squeezed together, against the action of the spring 24, so as to open the two jaws of the waver for reception of the ends of the hair to be waved or curled between said jaws. The jaws are then closed, by releasing the pressure on the finger grip portions, to clamp the ends 85 of the hair, after which the hair is rolled or wound on the device until a roll of the desired thickness has been formed thereon. The free end of the elastic cord is now carried forward over the roll of hair and secured to the 90

front end of member 10, thereby fastening the device in the hair and holding the roll in place. In using the device, it is preferable first to moisten or dampen the hair slightly, 5 and to leave the device in the hair a sufficient length of time to permit the wave or curl to set.

One of the distinctive features of the present improvement is that the elastic cord is 10 flexibly secured to the rear end or finger gripping portion of the device and extends rearwardly so as to be out of the way except when it is positioned to clamp the hair. This 15 construction prevents the elastic cord from disturbing the wave or curl after it has been formed. When the wave or curl has been set, the free end of the elastic cord is disengaged and said cord is returned to its normal rearwardly extending position shown in Figure 20 1. A slight pressure is now applied to the finger grips so as to open the jaws slightly, and the device is then withdrawn lengthwise from the hair. It will be noted that as the 25 elastic cord is first swung out of the way before withdrawing the device from the hair, any likelihood of disarranging the wave or curl through contact with the elastic cord on withdrawing the device is eliminated.

What I claim is:—

- 30 1. A hair waver comprising a tubular member, a member fitting on the tubular member, both of said members having finger grip portions at their rear ends and being pivotally connected together adjacent to said 95 ends, a spring disposed between the finger grip portions for urging said members closed, an elastic clamping cord extending normally rearwardly from the rear end and secured at one end to the spring, and means on the free 100 end of the cord for detachably securing said end to the front end of the tubular member.
- 40 2. A hair waver comprising a tubular member, a member fitting on the tubular member, both of said members having finger grip portions at their rear ends and being pivotally connected together adjacent to said ends, a spring disposed between the finger grip portions for urging said members closed, an elastic clamping cord extending normally 105 rearwardly from the rear end and secured at one end to the spring, and a hook on the free end of the cord adapted to catch in the open front end of the tubular member.
- 45 3. A hair waving device comprising a pair of pivotally connected cooperating members each having a finger grip portion at its rear end, a U-shaped leaf spring disposed between the finger grip portions for urging said members closed, and an elastic clamping cord provided at its front end with a forwardly protruding lug having a slot through which the leaf spring passes, said cord having means 110 at its rear end for detachably fastening said end to the front end of the device.
- 55 4. A hair waving device comprising a pair 115 of pivotally connected cooperating members each having a finger grip portion at its rear end, a U-shaped leaf spring disposed between the finger grip portions for urging said members closed, and an elastic clamping cord provided at its front end with a forwardly protruding lug having a slot through which the leaf spring passes, said cord having means 120 at its rear end for detachably fastening said end to the front end of the device.

of pivotally connected cooperating members each having a finger grip portion at its rear end, a U-shaped leaf spring disposed between the finger grip portions for urging said members closed, and an elastic clamping cord 70 provided at its front end with a forwardly protruding lug having a slot through which the spring passes, said cord having a hook at its rear end for detachably fastening said end to the front end of the device.

Signed at New York in the county of New York and State of New York this 11th day of February A. D. 1932.

ABRAHAM GOODMAN.
